CLAIM

The ornamental design for a road reflector or similar article, as shown and described.

DESCRIPTION

FIG. 1 is a front elevational view of a road reflector or similar article showing our new design, the opposite rear side being identical to the side shown;

FIG. 2 is a side elevational view taken from the left of FIG. 1, the opposite side being a mirror image thereof;

FIG. 3 is a top plan view thereof; and

FIG. 4 is a bottom plan view thereof.

FIG. 2

FIG. 1

FIG. 4

FIG. 3
